UNITED STATES PATENT OFFICE.

HERBERT I. ALLEN, OF PORTLAND, MAINE, ASSIGNOR TO ELECTRON CHEMICAL COMPANY, OF PORTLAND, MAINE, A CORPORATION OF MAINE.

ELECTROLYTIC CELL.

1,368,010.

Specification of Letters Patent.

Patented Feb. 8, 1921.

Application filed April 29, 1920. Serial No. 377,536.

To all whom it may concern:

Be it known that I, HERBERT I. ALLEN, a citizen of the United States, residing at Portland, in the county of Cumberland and 5 State of Maine, have invented new and useful Improvements in Electrolytic Cells, of which the following is a specification.

This invention has relation to electrolytic cells such as employed in the electrolytic 10 decomposition of saline solutions for the production of chlorin and caustic soda.

The object of the invention is to provide a cell of simple construction in which there is a maximum active anode and cathode area, 15 and in which the voltage may be low and the current efficiency high. The object of the invention is attained by a construction in which the cathode is formed with a plurality of vertical grooves or corrugations, to 20 register with spaced vertical anodes.

On the accompanying drawings,—

Figure 1 illustrates in side elevation a cell embodying the present invention.

Fig. 2 represents a vertical longitudinal 25 section through the same.

Fig. 3 represents a horizontal section on the line 3—3 of Fig. 2.

Fig. 4 represents an end elevation of the cathode.

Fig. 5 represents a side elevation of the 30 same, a part being broken away.

Fig. 6 represents an isometric perspective of a portion of the cathode.

Before proceeding to describe the particular embodiment of the invention which is 35 illustrated in the drawings thus briefly referred to, I desire to have it understood that the improvements to be described may be embodied in cells of other constructions.

40 In the cell as illustrated, I employ a rectangular tank or container 10, which may be made of sheet metal and which is relatively long and narrow. From the bottom of this tank leads an eduction pipe 11, by which 45 effluent from the cell may be conducted to a suitable receptacle and finally treated for the removal of the contained salt.

Resting on the upper end of the tank, 50 there is what may be termed a freeboard section in which the liberated chlorin is collected. This freeboard section is formed of some inert material, such as slate or the like, and it comprises side walls 12 and end walls 13. It is closed by a cover 14 of inert 55 material, the cover being perforated to re-

ceive the anodes as will be explained. It will be understood, of course, that the cover is provided with a dome or outlet through which the chlorin may be drawn for storage or use. As illustrated, the anode, considered as a whole, consists of a plurality of bars 15 of suitable material such as carbon, and, although these bars are illustrated as cylindrical or round in cross-section, they may be rectangular or prismatic if desired. 60 As shown, these bars are arranged in two rows, those at the ends of the respective rows being a little closer together than the remainder.

The cathode in the present case is illustrated as being formed somewhat like a basket or in approximately rectangular form so that it will fit within the tank and be spaced from the walls thereof. The cathode is made of sheet metal and it comprises side 70 and end walls 16, 17, at the upper ends of which is a continuous lateral flange 18 which is of such diameter that it may rest upon the end and side walls of the tank 10. The bottom of the cathode is formed of a plate 19. 80 The flange 18 is imperforate, but the side, end and bottom walls of the cathode are provided with apertures or slots which are closely spaced together to permit the passage of the effluent of the cell therethrough. 85 If desired, these slots may take the form of what are known as "herringbone" slots, as illustrated in Figs. 3, 4, 5 and 6.

I have stated that the anode as a whole 90 consists of spaced vertical bars, and it will be observed, from an examination of Fig. 3, that the side and end walls of the basket or cathode are provided with grooves or corrugations 19, 20, so that each bar is more or less inclosed by a concavo-convex portion 95 of the cathode wall. The four end bars of the anode are practically inclosed throughout an arc of 270°, whereas the remaining bars are inclosed throughout an arc of approximately 180°. The inclosing curved 100 walls of the cathode are approximately concentric with the respective anode bars but are spaced therefrom a short distance so that there is no contact between them.

In the space between the anode bars and the cathode, I place a diaphragm of asbestos paper or equivalent porous material which will permit a relatively free percolation of the electrolyte. This diaphragm is indicated 105 at 21. In placing it within the basket, I 110

take a long strip of asbestos paper and lay it against the side and end walls of the cathode and against the interior faces thereof, and fold the upper projecting edge of the paper outwardly so that it will overlie the flange 18. A second piece of the paper is died or cut out so that it will fit within the cathode and rest upon the bottom wall thereof, and then a narrow strip of the asbestos paper, which is coated with sodium silicate, is fitted within the reentrant angle formed by the side and bottom walls of the cathode so as to prevent the escape of the electrolyte at the juncture of the bottom and side walls 15 of the diaphragm.

It will be understood, of course, that if the anode bars are square or otherwise of angular formation, viewed in cross-section, the corrugations or grooves in the side and 20 end walls of the basket cathode will be complementally shaped to receive them.

The basket cathode is clamped to the freeboard section so that it will depend or hang within the tank 10. For this purpose, I use 25 a rectangular frame 23, between which and the lower end of the freeboard section are located the flange 18 of the cathode and the out-turned edge of the diaphragm. Suitable bolts, as indicated at 24, are employed to 30 clamp the cover 14, the freeboard section, the rectangular hollow frame 23, the flange 18 and the out-turned edge of the diaphragm all tightly together. As a result of 35 this construction and arrangement of parts, the freeboard section, the anodes and the cathode may be bodily lifted from the tank, the frame 23 resting loosely on top of the tank as shown.

The anode bars are supported upon the 40 bottom wall of the cathode, but are spaced therefrom by upright glass or porcelain studs 25, the heads of which rest upon the bottom of the cathode and the shanks of which fit in recesses 26 formed in the bottom 45 of the anode bars 15.

From the foregoing description, it will 50 be seen that, in a cell of given dimensions, I have secured a maximum active area of the cathode and the anodes, this area being greatly increased by the formation of the 55 cathode with its vertical corrugations by which the anode bars are partially inclosed by the cathode walls. The lower ends of the anode bars and the bottom of the cathode are likewise active. In the operation of the 60 cell, the faces of the anode, which confront the active faces of the cathode, become worn or disintegrated after some time, and the space between the anode bars and the cathode gradually increases in width. With the construction illustrated, however, it is 65 possible to rotate each of the anode bars through an angle of approximately 180° so as to bring an unworn or new face of the bar in proximity to the cathode, and thus

restore the original space between these parts. It is furthermore easy to remove any one of the bars since it may be lifted vertically from the freeboard section and the cathode, and replace it with a fresh bar. Of course, it will be understood that a suitable bus-bar connection is employed for leading current to the anodes and that an electrical connection is made with the cathode for carrying away current.

It will be further seen from the construction described that the voltage of the cell is reduced since the distance which the current must traverse through the electrolyte from any point on one of the anode bars to the cathode is very small. Of course, care must be taken to see that the electrolyte is substantially saturated with salt and that the current is not wasted in decomposing the water of the solution.

With a cell of this construction in a given floor space in a cell plant, it is possible to either run an ordinary electrolytic cell load at a greatly reduced voltage or else to run a greatly increased load at a voltage which would be no higher than that of cells without the features as herein described.

I do not herein specifically claim the structure disclosed and claimed in my copending application Serial No. 377,537, filed April 29, 1920.

Having thus explained the nature of my said invention and described a way of making and using the same, although without attempting to set forth all of the forms in which it may be made or all of the modes of its use, what I claim is:

1. In an electrolytic cell, an anode consisting of one or more rows of vertical bars, and a cathode having a vertical wall spaced from said bars, said wall being formed with vertical perforated corrugations registering with said bars.

2. In an electrolytic cell, a basket-shaped cathode having corrugations in its side walls.

3. In an electrolytic cell, a basket-shaped cathode having vertical corrugations in its side walls.

4. In an electrolytic cell, a basket-shaped cathode having corrugations in its side and end walls.

5. In an electrolytic cell, a basket-shaped cathode having an out-turned flange at its upper end, and having perforated corrugations in its side walls.

6. In an electrolytic cell, a basket-shaped cathode having at its upper end an imperforate flange projecting outwardly from its end and side walls, the side walls of said cathode being formed with perforated corrugations.

7. In an electrolytic cell, an anode consisting of parallel spaced bars, and a basket-shaped cathode inclosing said bars, said cathode being formed with perforated cor-

- rugations registering with said bars, and a porous diaphragm located between the anode and the cathode and bearing against the inner faces of said corrugations.
- 5 8. In an electrolytic cell, a tank, a free-
board section supported on said tank, a basket-like cathode secured to said freeboard section and hanging into the tank, and an anode in said cathode and consisting of 15
- 10 a plurality of spaced bars, said cathode having corrugations in its side walls registering with said bars. 20
9. In an electrolytic cell, a tank, a free-

board section supported on said tank, a basket-like cathode secured to said freeboard section and hanging into the tank, and an anode in said cathode and consisting of a plurality of vertical spaced bars, said cathode having vertical perforated corrugations in its side walls, and having an out-turned flange at its upper end by which it is secured as aforesaid to said freeboard section.

In testimony whereof I have affixed my signature.

HERBERT I. ALLEN.
